CONVERSION ARRANGEMENT FOR VACUUM CLEANERS

Earl B. Hough, Detroit, Mich., assignor to Eureka
Williams Corporation, a corporation of Michigan

Application June 11, 1943, Serial No. 490,525

10 Claims. (Cl. 15—332)

1

This invention relates to vacuum cleaners and has particular reference to a novel and very efficient manner of and means for converting a floor type cleaner into one adapted for so-called "off the floor" cleaning.

My invention has particular application to that type of floor cleaner having a vertical driving motor, a fan driven thereby, a floor nozzle having a communication with said fan and having a surface cleaning member associated therewith, and a driving connection arranged in said communication and extending between said motor and said surface cleaning member for actuating the latter, and as illustrated in the embodiments of the invention selected for purposes of illustration, consists of a device built into the cleaner and cooperable with said driving connection for rendering the same inoperative and operative, and a coupling insertable in said communication so as to shut off the flow of air from the floor nozzle to the fan and which coupling is adapted to have suction cleaning tools connected therewith, said communication having a normally closed port in which said coupling is insertable and said port having a cover therefor, and said device being actuated by movement of the cover between closed and open position for breaking and remaking the driving connection.

In its broadest aspect my invention contemplates the provision of a means for preventing the connection of the converter coupling to the machine when the agitator is being driven by the motor of the cleaner.

Principal objects of the invention are:

To provide a means for preventing the connection of the converter coupling to the machine when the agitator thereof is being driven by the motor;

To provide a means for opening the motor circuit before the converter coupling is connected to the machine; and

To provide a means to prevent the disengagement or the engagement of the driving connection when the motor of the machine is operating.

Other objects and advantages of the invention will be apparent from a consideration of the following specification taken in conjunction with the accompanying drawings, of which there are four sheets and wherein:

Fig. 1 is a perspective view of a floor type vacuum cleaner embodying the invention, with a hose and dusting tool attached thereto for "off the floor" cleaning;

Fig. 2 is an elevational view, with certain parts shown in section, of a cleaner embodying the in-

2

vention and arranged for "on the floor" cleaning;

Fig. 3 is a fragmentary view similar to Fig. 2 but illustrating the manner in which an attachment converter is connected to the machine;

Fig. 4 is a fragmentary horizontal sectional view of the machine and illustrating a modified form of interlock between the converter port cover and the circuit of the cleaner motor;

Fig. 5 is a fragmentary vertical sectional view of a modified form of the invention illustrating the belt lifting mechanism of the cleaner when the same is arranged for "on the floor" cleaning;

Fig. 6 is a fragmentary horizontal sectional view with the parts arranged as illustrated in Fig. 5;

Fig. 7 is a fragmentary vertical sectional view of the embodiment illustrated in Fig. 5;

Fig. 8 is a horizontal sectional view of the belt lifter mechanism of the embodiment positioned as illustrated in Fig. 7;

Fig. 9 is a vertical sectional view taken along the line 9—9 of Fig. 5; and

Fig. 10 is a vertical sectional view taken along the line 10—10 of Fig. 7.

Floor type cleaners with which my new and improved conversion means are particularly useful are illustrated in Figs. 1, 2 and 5, and include a vertical electric motor 20 forming a driving means for a suction creating means which includes a fan 22 arranged in a fan chamber 24, the fan 22 being secured to the shaft 25 of the motor 20 for rotation therewith. The fan chamber is provided with an inlet 26 formed by a fan eye and an outlet 28 to which a dust collecting receptacle 30 is connected. The cleaner further includes a rotary surface cleaning member or agitator 32 which is rotatably mounted within the floor nozzle 34, the mouth 36 of the nozzle being normally positioned slightly above the surface upon which the cleaner is supported for movement by front and rear wheels 38 and 40. An air flow communication 42 connects the nozzle 34 with the fan 22 through the inlet 26 so that upon operation of the fan, dirt laden air is drawn through the mouth 36 of the nozzle and conducted to the receptacle 30 which is connected to the fan discharge 28.

The design of the cleaner illustrated in Figs. 2 and 3 is in some respects slightly different from that illustrated in Figs. 5 and 6, the construction and operation of the belt shifting mechanism, motor, fan, nozzle, and brush being the same.

The cleaner is provided with a handle 44 by means of which the machine may be maneuvered over a surface or surface covering which is to be

cleaned by the machine. When the cleaner is operated on a surface covering such as a rug, the suction at the mouth of the nozzle induced by operation of the fan draws such surface covering up against the mouth 38 of the nozzle where it is acted upon by the rotary surface cleaning member 32, in this case a rotary brush having bristles 46 which are adapted to sweep and/or beat the carpet to expedite the cleaning thereof.

The fan 22, as previously indicated, is secured to the vertical motor shaft 25 for rotation therewith and may consist of a series of blades extending in a general radial direction from a hub 48, said hub forming a continuation of the shaft 25 of the motor and extending through the fan inlet 28 substantially at the center thereof and in spaced relation with the edges defining such fan inlet or inlet opening 28. The inlet opening 28, as illustrated, comprises a central circular opening on the under side of the fan chamber 24 having its center substantially coinciding with the center of the hub 48. The hub 48 projects downwardly into the communication 42 at one end thereof and is formed to provide a pulley 50 having an endless elastic belt 52 associated therewith so as to be driven thereby. The belt 52 has driving engagement with a pulley 54 suitably formed on the rotary brush 42 adjacent the center thereof so that normally during operation of the motor 20 the fan 22 and the agitator 32 will be driven. As illustrated in Fig. 5, the belt 52 is arranged in and extends through the communication 42 between the nozzle 34 and the fan inlet opening 28, the communication 42 at its forward end opening into the nozzle 34.

The communication 42, except for the removable section 56, may be formed integrally with the body of the cleaner which may consist of a casting suitably formed to provide the fan chamber 24, the communication 42, and the nozzle 34. The communication 42 is provided with an upwardly facing opening or port 58 in its upper wall and which port is positioned at or adjacent the front of the cleaner near the center thereof and between the fan and the nozzle thereof. This port 58, which may hereinafter be designated as a converter port, is adapted to be closed by a suitable cover 60 so that when the machine is used for "on the floor" cleaning, the port 58 is closed. The port 58 consists of an opening to which a converter coupling may be connected so that the machine may be converted and used for "off the floor" cleaning. The cover 60 overlies the upper wall of the passageway 42 about the port 58 and may be pivoted as indicated at 62 to a part of the cleaner casting and for movement between the positions illustrated in Figs. 2 and 3. When the cover 60 is open, that is, arranged as illustrated in Fig. 3, a converter coupling 64 is adapted to be connected to the port 58 and thereby to the cleaner. The coupling 64 comprises a hollow air conducting member to which one end of a flexible air conducting hose 66 is, or is adapted to be, connected, the other end of the hose having provision for connecting a suitable cleaning tool such as that illustrated at 68, thereto.

An arm 70 is fixed to the cover 60 to move therewith and this arm is positioned exteriorly of and alongside the outer wall of the passageway 42 as illustrated in Fig. 4. A link 72 connects the arm 70 with an arm 74 of a gear sector 76 (Fig. 6) of the belt shifting mechanism for shifting the same between its two positions, as will be herein-after explained. At this point, suffice it to say

that when the cover 60 is closed, the belt shifting mechanism is arranged as illustrated in Fig. 5 and so that the belt 52 is in driving relationship with the pulley 50. When the cover 60 is opened or positioned as illustrated in Fig. 3, the arm 70 through the linkage just described has actuated the belt shifting mechanism so as to disengage the belt 52 from driving relationship with the pulley 50. Of course, when the belt 52 is disengaged from the pulley 50, the driving connection between the motor 20 and the agitator 32 is broken. Therefore it follows that when the port 58 is closed, the agitator 32 is adapted to be driven by the motor 20 during the operation thereof, and when the port 58 is open or positioned as illustrated in Fig. 3, the motor 20 may be operated without driving the agitator 32.

In order to prevent the belt shifting mechanism from breaking the driving connection between the motor 20 and the agitator 32 during the time that the motor 20 is operating, a means is provided to prevent this and, as illustrated in Figs. 2 and 3, comprises a means for opening the motor circuit when the cover 60 is opened. A part of the motor circuit is illustrated in Fig. 2 and consists of a conductor 80 connected to one of the terminals 82 of the motor 20. Another conductor 84 connected to the other terminal 86 of the motor is connected to one terminal 88 of a switch 90, the other terminal 92 of the switch having connected to it a conductor 94 which together with the conductor 80 leads to the manually operated switch which is normally positioned on the handle 44 of the cleaner so as to enable the motor of the machine to be turned off and on conveniently.

The switch 90 includes movable and stationary contacts 98 and 96, the contact 98 being carried by a spring arm 100. A lever 102 pivoted at 104 to the body of the cleaner and biased in a counterclockwise direction by a spring 106 has an arm 108 which is adapted to engage a hump 110 on the arm 100 and hold the contacts 96, 98 closed when the cover 60 is positioned as illustrated in Fig. 1. Shifting of the cover to the position illustrated in Fig. 3 will enable the spring 106 to move the lever out of the path of the hump 110, thereby permitting the contacts 96 and 98 to separate and thereby open the motor circuit. The switch 90 of course will be closed if the cover 60 is returned to the position illustrated in Fig. 2. The switch 90 is also adapted to be closed by the insertion of a converter coupling 64 into the converter port 58 and to this end the coupling 64 carries an arm 112 (Fig. 3) which is adapted to engage an end 114 of the lever 102 and actuate the lever to close the switch 90 when the coupling 64 is properly positioned in the port 58. In Fig. 3 the coupling 64 has been inserted in the port but is not fully seated therein inasmuch as the bottom of the coupling 64 is not seated on the bottom wall of the passage 42.

Further particulars regarding the construction and the operation of the coupling are set forth in connection with the description of Figs. 8-10. Suffice it to say that when the coupling 64 is properly seated in the port 58, the mechanism just described will close the switch 90 and thereby close the motor circuit, assuming that it was closed at the time that the door 60 was opened. The switch 90 and the mechanism for opening and closing the same thus comprise a means for preventing the connection of the coupling 64 to the cleaner when the motor is driving the agitator, or otherwise stated, the switch 90 forms

a part of an interlock between the converter port closure 60 and the motor circuit. It will also be appreciated that as soon as the coupling 64 is separated from the converter port 58 and from the cleaner, that the motor circuit will be opened, thereby preventing the separation of the coupling from the cleaner during the operation of the motor, as well as preventing the reestablishment of the driving connection between the agitator 32 of the cleaner and the motor when the latter is in operation.

In Fig. 4 a modification of the interlock is illustrated and consists of a positive lock for preventing either opening or closing of the converter port cover 60 during the operation of the motor. In the modification illustrated in Fig. 4 the switch 90 has been eliminated and in its place a magnet at 116 is suitably affixed to the outer wall of the passage adjacent the path of movement of the arm or link 70. The magnet 116 is connected across the circuit of the motor as illustrated diagrammatically, the handle switch 120 previously referred to, of the motor circuit, being also diagrammatically illustrated.

The magnet 116 includes a laminated armature 122 pivoted at 124 and biased in a counterclockwise direction by spring 126. The armature 122 is provided with an arm or lock 128 which when the magnet is energized (that is, when the switch 120 is closed), is adapted to be positioned in the path of movement of the arm 70. The arm 70 (shown in section) in this view is illustrated in full lines in its position when the cover 60 is closed, and in dotted lines in its position when the cover 60 is open. When the motor circuit is open the arm or lock 128 is positioned by the spring 126 out of the path of movement of the arm 70. However, during the time that the motor 20 is driving the fan and the agitator of the cleaner and with the converter port cover 60 in its closed position, the arm 70 will be positioned as illustrated in full lines in Fig. 4 and the lock 128 will obstruct its path of movement, thereby preventing the opening of the converter port at such time.

If the circuit of the motor 120 is open, the lock 128 will shift to the dotted line position indicated, thereby permitting the arm 70 to shift from its full to its dotted line position as the cover 60 is opened. When the circuit of the motor 120 is again closed after the coupling 64 is connected to the converter port, the lock 128 will prevent the arm 70 from being shifted back to its full line position even though the coupling 64 might be separated from the port 58. However, as soon as the motor circuit is opened by the switch 120, the cover 60 may be shifted to its closed position. In this manner the belt shifting means cannot be operated either to engage or disengage the belt from its driving pulley 50 during the time that the motor 20 of the cleaner is operating.

In the embodiment of the invention illustrated in Figs. 5-10 inclusive, the construction of the cleaner and of the belt lifter mechanism thereof is essentially the same as that employed in the previous modifications, the principal difference, outside of the particular shape of some of the parts of the cleaner, being the provision of a different form of means for preventing the disengagement and reengagement of the belt from its driving pulley during the operation of the motor. The converter coupling illustrated in this embodiment is also the same as that illustrated in the previous embodiments.

The removable section 56 of the passage 42 sup-

ports the belt shifter mechanism which consists of a belt lifter or shifter 130 carried by an arm 132 which is pivoted at 134 to the bottom wall of the section 56. It should be observed that the shaft 134 of the belt shifter 130 is disposed off center relative to the driving pulley 50.

The pivot 134 consists of a pin fixed to the arm 132 to oscillate the same and having a gear 136 connected thereto for rotating the pin 134. The gear 136 meshes with the gear sector 76 so that when the arm 74 connected to the link 72 is shifted from the position illustrated in Fig. 6 to that illustrated in Fig. 8, the belt shifter 130 will be shifted from the position illustrated in Fig. 7 to that shown in Fig. 8 and vice versa. As previously described, the link 72 is connected to the arm 70 of the cover 60 so that when the cover 60 is closed the arm 74 is positioned as illustrated in Fig. 6, and when the cover 60 is open the arm 74 is positioned as illustrated in Fig. 8.

The belt lifter 130 extends vertically and is adapted to engage one strand of the belt 52, as it swings from the position in which it is illustrated in Fig. 6 in a counterclockwise direction about its pivot 134, thereby moving the belt out of driving relation with the pulley 50 as illustrated in Fig. 7. The sector 76 and gear 136 may be enclosed by a plate 140 affixed to the under side of the section 56 which in turn is removably secured in any desirable way to the cleaner so as to complete the passage 42. For example, the forward end of the section 56 may seat on a ledge 142 and the rear end of the section 56 may have a shoulder 144 engaged by a manually releasable latch 146. The belt lifter 130 projects upwardly from the bottom of the passage 42 between the strands of the belt 52, and forwardly of the pulley 50. The upstream side of the belt shifter may be suitably formed so as to prevent the collection of lint, threads, etc., thereon.

In this modification the means for preventing the connection of the converter coupling 64 to the machine when the motor is running consists of a rod 150 slidably mounted transversely of the passage 42. The end 152 of the rod projects through an opening in the walls of the passage and is adapted to obstruct the path of movement of the arm 70 during the operation of the fan. The other end of the rod 150 is connected to a diaphragm 154 which is sealed to the inside wall of the passage 42 as illustrated in Figs. 6 and 9. The space enclosed by the diaphragm may communicate with atmosphere through aperture 156. During the operation of the motor of the cleaner and of the fan, when the mouth 36 of the nozzle is operatively positioned adjacent the surface covering to be cleaned, the air pressure in the passageway 42 is below atmospheric, thereby displacing the diaphragm 154 to the right, looking at Fig. 9, and positioning the end 152 of the rod 150 in the path of movement of the arm 70. When the end 152 of the rod is in this position, the cover 60 cannot be opened or closed. However, when the motor is stopped the fan of the cleaner will stop and the air pressure in the passage 42 will rise to atmospheric pressure, whereupon spring 158 will move the end 152 of the rod out of the path of movement of the arm 70, thereby permitting the cover to be opened or closed.

The coupling 64 consists of a sleeve or coupler member 160 conforming in cross section to the shape of the port 58. The sleeve 160 is cut away to form a slot or notch 162 which is adapted to accommodate the strands of the belt 52 when

the bottom end of the sleeve 160 is seated upon the bottom wall of the passage 42 as illustrated in Fig. 10. As in some cases the passage 42 may be wider than the diameter of the sleeve 160, laterally extending wings 164 may be provided on the sleeve so as to close that part of the passage 42 not occupied by the sleeve 160.

The coupling 64 further includes a segment of a sleeve 166 arranged within the sleeve 160. Sleeve segment 166 includes a portion 168 which is adapted to close that part of the slot 162 not occupied by the strands of the belt 52. The sleeve segment 166 is cut away like the sleeve 160 so as to accommodate the strands of the belt 52 when the coupling is inserted in and removed from the cleaner, and the sleeves 160 and 166 are also cut away on the downstream side of the passage 42 so as to establish a communication between the fan inlet and the interior of the coupling 64. Thus when the coupling 64 is positioned in the cleaner as illustrated in Figs. 7 and 10 and when the portion 168 of the sleeve segment 166 obstructs that part of the slot 162 not occupied by the strands of the belt 52, the coupling 64 shuts off the communication between the nozzle 34 of the cleaner and the fan inlet 26 thereof.

As illustrated in Fig. 6, the upper wall of the passage is provided with two radially extending slots 170 and 172 which accommodate the wings 164. The slot 172 includes an offset portion which accommodates a lug 174 carried by the sleeve segment 166 and extending outwardly therefrom through a slot 176 formed in the sleeve 160. When the coupling 64 is inserted in or removed from the cleaner, the lug 174 is positioned adjacent one of the wings 164 so as to pass through the slot 172 and below the upper wall of the passage 42. After the lower end of the coupling is seated in the bottom wall of the passage 42 the sleeve segment 166 may be turned by means of the collar 178 which is affixed to the upper end thereof so as to move the lug 174 to the position illustrated in Fig. 7 and below the rim of the port 58, thereby preventing the separation of the coupling 64 from the cleaner. The coupling 64 may be internally provided with lugs indicated at 180 for cooperation with bayonet slots 182 formed in the end 184 of the hose 66 for securing the same to the cleaner.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. A floor type vacuum cleaner having a body and comprising an electric motor, a fan connected thereto and driven thereby during operation of the motor, said fan being arranged in a fan chamber provided with an air inlet, an air intake nozzle, said cleaner having a passage-way connecting said nozzle to said fan chamber through said inlet, an agitator operatively associated with said nozzle, a driving connection comprising a belt and pulley arranged in said passage-way and between said motor and said agitator for actuating the latter during operation of said fan and motor, said passage-way being provided with a converter port communicating with said fan chamber through said inlet thereof, a converter coupling comprising a hollow air conducting

member adapted to be connected with said port, means in said passage-way operable for disengaging said belt and pulley for breaking said driving connection between said motor and said agitator, an electric circuit for said motor, and means to prevent the connection of said converter coupling to said port and the operation of said means to disconnect said belt from said pulley while said circuit is closed.

2. A floor type vacuum cleaner having a body and comprising an electric motor, a fan connected thereto and driven thereby during operation of the motor, said fan being arranged in a fan chamber provided with an air inlet, an air intake nozzle, said cleaner having a passage-way connecting said nozzle to said fan chamber through said inlet, an agitator operatively associated with said nozzle, a driving connection comprising a belt and pulley arranged in said passage-way and between said motor and said agitator for actuating the latter during operation of said fan and motor, said passage-way being provided with a converter port communicating with said fan chamber through said inlet thereof, a converter coupling comprising a hollow air conducting member adapted to be connected with said port, means in said passage-way operable for disengaging said belt and pulley for breaking said driving connection between said motor and said agitator, means to prevent the connection of said converter coupling to said port and the operation of said means to disconnect said belt from said pulley while said motor is driving said agitator, said means comprising a cover adapted normally to close said converter port, and means to prevent movement of said cover which opens said port while said motor is operating.

3. A vacuum cleaner having a body and comprising an electric motor, a fan connected thereto and driven thereby during operation of the motor, said fan being arranged in a fan chamber provided with an air inlet, an air intake nozzle, said cleaner having a passageway connecting said nozzle to said fan chamber through said inlet, an agitator operatively associated with said nozzle, a driving connection comprising a belt and pulley arranged in said passageway between said motor and said agitator for actuating the latter during operation of said fan and motor, said passageway being provided with a converter port communicating with said fan chamber through said inlet thereof, a converter coupling comprising a hollow air conducting member adapted to be connected with said port, means operable for disengaging said belt from said pulley for breaking said driving connection between said motor and said agitator, means to prevent the connection of said converter coupling to said port while said driving connection is engaged, and means arranged to prevent the operation of said means for breaking said driving connection when said motor is operating.

4. A vacuum cleaner having a body and comprising an electric motor, a fan connected thereto and driven thereby during operation of the motor, said fan being provided with an air inlet, an air intake nozzle, said cleaner having a passageway connecting said nozzle to said fan through said inlet, an agitator operatively associated with said nozzle, a driving connection comprising a belt and pulley arranged in said passage-way and between said motor and said agitator for actuating the latter during operation of said fan, said passage-way being provided with a converter port communicating with said fan through said inlet

thereof, a converter coupling comprising a hollow air conducting member adapted to be connected with said port, means in said passage-way operable for disengaging said belt from said pulley for breaking said driving connection between said motor and said agitator, an electric circuit for said motor, means to prevent the connection of said converter coupling to said port while said driving connection is engaged, means for opening said motor circuit, and means arranged to prevent the operation of said means for breaking said driving connection when said motor circuit is closed.

5 5. A vacuum cleaner having a body and comprising an electric motor, a fan connected thereto and driven thereby during operation of the motor, said fan being provided with an air inlet, an air intake nozzle connected to said fan through said inlet, an agitator operatively associated with said nozzle, a driving connection comprising a belt and pulley between said motor and said agitator for actuating the latter during operation of said fan, a passageway extending between said fan air inlet and said nozzle and in which said belt and pulley are arranged, said passageway being provided with a converter port communicating with said fan through said inlet thereof, a converter coupling comprising a hollow air conducting member adapted to be connected with said port, means operable for disengaging said belt from said pulley for breaking said driving connection between said motor and said agitator, means to prevent the connection of said converter coupling to said port while said driving connection is engaged, an electric circuit for said motor, and an interlock between said means for breaking said driving connection and said motor circuit which requires that said circuit be open before said means for breaking said driving connection is operated.

6. A vacuum cleaner having a body and comprising an electric motor, a fan connected thereto and driven thereby during operation of the motor, said fan being arranged in a fan chamber provided with an air inlet, an air intake nozzle connected to said fan chamber through said inlet, an agitator operatively associated with said nozzle, a driving connection between said motor and said agitator for actuating the latter during operation of said fan and motor, said cleaner being provided with a converter port communicating with said fan through said inlet thereof, a converter coupling comprising a hollow air conducting member adapted to be connected with said port, means operable for breaking said driving connection between said motor and said agitator, a cover adapted normally to close said converter port and movable between closed and open positions, means to prevent the connection of said converter coupling to said port while said driving connection is engaged, and suction operated means operable to prevent opening of said cover during operation of said motor.

7. A vacuum cleaner having a body and comprising an electric motor having a vertical shaft, a fan arranged in a fan chamber below said motor and connected to said shaft to be driven thereby, said fan chamber being provided with an air inlet on the under side thereof, a nozzle having a downwardly presented mouth, and an agitator operatively associated therewith, said cleaner being provided with wheels for movably supporting the same, means forming an air passageway between said nozzle and said fan chamber inlet for inducing a flow of air into said nozzle during operation of said fan, said passageway being provided with a converter port, a converter coupling

comprising a hollow air conducting member adapted to be connected with said port, said shaft extending through said fan chamber inlet into said passageway, a belt arranged in driving relationship with said shaft and agitator for actuating the latter during operation of said fan and motor, belt shifting means for lifting the belt out of driving relationship with said shaft, a cover for said port, and suction operated means to prevent opening of said cover when said fan is operating.

8. A floor type vacuum cleaner having a body and comprising an electric motor, a fan connected thereto and driven thereby during operation of the motor, said fan being arranged in a fan chamber provided with an air inlet, an air intake nozzle, said cleaner having a passageway connecting said nozzle to said fan chamber through said inlet, an agitator operatively associated with said nozzle, a driving connection comprising a belt and pulley arranged in said passageway and between said motor and said agitator for actuating the latter during operation of said fan and motor, said passageway being provided with a converter port communicating with said fan chamber through said inlet thereof, a pivoted handle for maneuvering said cleaner over a surface covering to be cleaned with said nozzle and agitator operatively positioned relative to said surface covering, a converter coupling comprising a hollow air conducting member adapted to be connected with said port, means in said passageway operable in all positions of said handle for disengaging said belt and pulley for breaking said driving connection between said motor and said agitator, and means to prevent the connection of said converter coupling to said port and the operation of said means to disconnect said belt from said pulley while said motor is operating and driving said agitator.

40 9. A floor type vacuum cleaner having a body and comprising an electric motor, a fan connected thereto and driven thereby during operation of the motor, said fan being arranged in a fan chamber provided with an air inlet, an air intake nozzle, said cleaner having a passageway connecting said nozzle to said fan chamber through said inlet, an agitator operatively associated with said nozzle, a driving connection comprising a belt and pulley arranged in said passageway and between said motor and said agitator for actuating the latter during operation of said fan and motor, said passageway being provided with a converter port communicating with said fan chamber through said inlet thereof, a pivoted handle for maneuvering said cleaner over a surface covering to be cleaned with said nozzle and agitator operatively positioned relative to said surface covering, a converter coupling comprising a hollow air conducting member adapted to be connected with said port, means in said passageway operable in all positions of said handle for breaking said driving connection between said motor and said agitator, a member adapted to obstruct said converter port, and means to prevent opening movement of said member to a non-obstructing position relative to said port and the operation of said means to break said driving connection when said motor is energized.

70 10. A floor type vacuum cleaner having a body and comprising an electric motor, a fan connected thereto and driven thereby during operation of the motor, said fan being arranged in a fan chamber provided with an air inlet, an air intake nozzle, said cleaner having a passageway connecting said nozzle to said fan chamber

11

through said inlet, an agitator operatively associated with said nozzle, a driving connection comprising a belt and pulley arranged in said passageway and between said motor and said agitator for actuating the latter during operation of said fan and motor, said passageway being provided with a converter port communicating with said chamber through said inlet thereof, a pivoted handle for maneuvering said cleaner over a surface covering to be cleaned with said nozzle and agitator operatively positioned relative to said surface covering, a converter coupling comprising a hollow air conducting member adapted to be connected with said port, means in said passageway operable in all positions of said handle for disengaging said belt and pulley for breaking said driving connection between said motor and said agitator, an electric circuit for said motor, means to prevent the connection of said converter coupling to said port and the operation of said means to disconnect said belt from said pulley while said circuit is closed, said means comprising a member adapted normally to obstruct said converter port

5 so as to prevent the insertion of said converter coupling therein, and means to prevent movement of said member to a non-obstructing position relative to said converter port when said motor circuit is closed.

12 EARL B. HOUGH.
